UNITED STATES PATENT OFFICE.

ADOLPH M. HOLSTEIN, OF SYRACUSE, NEW YORK.

DESIGN FOR A DECORATIVE TRIMMING FOR FURNITURE, CASKETS, OR SIMILAR ARTICLES.

52,441.

Specification for Design.

Patented Sept. 17, 1918.

Application filed November 26, 1917. Serial No. 204,106. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for Decorative Trimmings for Furniture, Caskets, or Similar Articles, of which the following is a specification, reference being had to the accompanying drawing, forming a part hereof.

The drawing is a face view of this design.

This design comprehends the representation of an urn in the shape of a conven-

tional husk filled with roses and other flowers, buds and leaves and resting on conventional foliated scrolls spreading laterally and upwardly to the right and left of the urn.

I claim:

The ornamental design for a decorative trimming for furniture, caskets or similar articles, substantially as shown.

In testimony whereof, I have hereunto signed my name, at Syracuse, in the county of Onondaga, and State of New York, this 6th day of October, 1917.

ADOLPH M. HOLSTEIN.
